UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-CONTAINER.

53,303.

Specification for Design.

Patented May 13, 1919.

Application filed February 19, 1915. Serial No. 9,450. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Powder-Container, of which the following is a specification, reference being had to the accompanying drawing, forming a part thereof.

On the drawing the figure is a perspective view of a container embodying the said design.

The design is characterized by a wide and flat cylindrical body and cover having on

the top an upwardly extending cylindrical neck and sifter cap, the cover being formed on its side wall near the top with an outwardly extended and rounded bead, and the cover and body below said bead being plain and having no outward extension.

I claim:—

The ornamental design for a powder container, as shown and described.

EDMUND HOFFMAN.
